CRASH HELMET

Jacques Spreiregen, London, England

Application June 3, 1955, Serial No. 36,362

Term of patent 14 years

(Cl. D3—13)

FIG. 1

FIG. 2

FIG. 3

FIG.4

FIG.5

Fig. 1 is a front view of a crash helmet showing my new design;

Fig. 2 is a side elevational view thereof looking from the left of Fig. 1;

Fig. 3 is a side perspective view showing the side opposite to that shown in Fig. 2;

Fig. 4 is a top plan view; and

Fig. 5 is a bottom plan view thereof.

I claim:

The ornamental design for a crash helmet, as shown.
